UNITED STATES PATENT OFFICE

132,794

DESIGN FOR A BROOCH OR SIMILAR ARTICLE

Joseph J. Sharkey, Los Angeles, Calif.

Application February 4, 1942, Serial No. 105,634

Term of patent 3½ years

To all whom it may concern:

Be it known that I, Joseph J. Sharkey, a citizen of the United States of America, residing in the county of Los Angeles, State of California, have invented a new, original, and ornamental Design for a Brooch or Similar Article, of which the following is a specification, reference being had to the accompanying drawing, forming a part thereof.

I claim:

The ornamental design for a brooch or similar article, as shown.

JOSEPH J. SHARKEY.
